UNITED STATES PATENT OFFICE.

CARL D. KELLEY, OF LAWRENCE, KANSAS.

AUTOMATIC GATE.

1,356,989.

Specification of Letters Patent. Patented Oct. 26, 1920.

Application filed February 7, 1920. Serial No. 356,811.

To all whom it may concern:

Be it known that I, CARL D. KELLEY, a citizen of the United States, residing at Lawrence, in the county of Douglas and State of Kansas, have invented a new and useful Automatic Gate, of which the following is a specification.

This invention relates to gates, and more particularly to automatic gates.

10 The primary object of the invention is to provide a gate adapted to swing in a vertical plane, and one which will be normally held in a vertical or closed position.

15 A further object of the invention is to provide a gate, adapted to be operated by the force of a vehicle, moving into engagement therewith, thereby moving the gate from a vertical or closed position, to a horizontal, or open position, to permit the vehicle to pass thereover.

20 A further object of the invention is to provide a device of this character, which will automatically move to its closed position, after a vehicle has passed thereover.

25 A further object of the invention is to provide a gate, having means for preventing the gate from moving to its closed position, until the vehicle passing through the gate, has entirely cleared the gate.

30 With the above and other objects in view, which will appear as the description proceeds, the invention resides in the combination and arrangement of parts and in the details of construction hereinafter described and claimed, it being understood that various changes in the precise embodiment of the invention shown can be made without departing from the spirit of the invention.

35 Referring to the drawings:

10 Figure 1 illustrates a view in elevation, of a gate constructed in accordance with the present invention.

Fig. 2 illustrates a side elevational view, partly in section, showing the gate in a semi-open position, and

Fig. 3 illustrates a detail view of the hinge employed in connection with the gate.

Having reference to the drawings in detail, the reference characters 5 and 6 designate the side posts of the gate, which are preferably hollow throughout their lengths, the lower ends thereof being embedded in a concrete foundation 7, but it is to be understood that any suitable form of foundation, which will securely anchor the posts 5 and

6 in their vertical positions, may be employed.

Disposed between the posts 5 and 6, and constructed to operate in a vertical plane, is the gate proper 8, which includes the top and bottom bars 9 and 10 respectively, which bars are connected by the end bars 11 and 12, all of the bars, being connected by a suitable, substantially heavy, wire mesh 13, but it is of course apparent that the mesh employed in the gate construction, should conform to the type of mesh used in the construction of the fence associated therewith.

The gate construction also includes the central bar 14, which has its ends connected to the bars 9 and 10, by means of the couplings 15, the horizontally disposed buffer bar 16, having connection with the central bar 14, intermediate its length, the ends thereof having connection with the end bars 11 and 12, as at 17. This buffer bar 16, is disposed in suitable spaced relation with the bottom bar 10, so that the same will be engaged by the periphery of the front 80 wheels of a vehicle, passing through the gate, the buffer bar being for the purpose of receiving the strain, or shock directed to the gate, during the opening operation.

85 Hinge members 18, which are in the form of cleats, are constructed to embrace the lower bar 10 of the gate, the same being disposed in suitable spaced relation throughout the length of the lower bar 10, whereby the gate is uniformly supported to permit 90 the same to move freely, during the opening and closing operations.

95 As shown, these cleats, are preferably semi-circular in formation, to conform to the contour of the lower bar 10, so that the gate will be free of lateral movement within the hinge elements 18. Supported under each of the hinge elements 18, is a relatively flat member 19', which is provided with openings, in its respective ends, which openings register with the openings 20, formed in the right angled ends 21, forming a part of the respective cleats. Bolts 22 pass through the registering openings 20 and 23, the ends of said bolts passing into the foundation, supporting the gate, where the same are anchored by any suitable means not shown.

100 Secured to the respective end bars 11 and 12 are the bracket members 19 and 20, the bracket members 19, being supported sub- 110

stantially intermediate the lengths of the bars 11 and 12, and provide means for securing the free ends of the flexible members 24, to the gate, the opposite ends of said flexible members 24, having connection with the weights 25 and 26 respectively, the intermediate portions of the flexible members 24 passing over the pulleys 25, supported to operate in a vertical plane, adjacent the upper ends of the posts 5 and 6, the pulleys 27, being arranged in pairs, to operate in a vertical plane, and provide guides for the flexible members 24, to prevent the flexible members from being displaced from the pulleys 25, when lateral strain is brought to bear on the flexible members 24, during the opening and closing operations.

If it becomes necessary to hold the gate, in its open position, it is only necessary to move the connection between the gate and flexible members, to the bracket members 20, which, due to their locations with respect to the pivot point of the gate, tend to prevent closing of the gate. The extension 26', forms a continuation of the central bar 14, and is provided for the purpose of contacting with the body of the vehicle passing thereover, for holding the gate in an open position, and preventing the same from closing, before the vehicle, has cleared the gate.

From an observation of Fig. 2, it will be apparent that in operation a vehicle to pass through a gate constructed in accordance with the present invention, moves into engagement with the buffer bar 16, whereupon further movement of the vehicle causes the gate proper to move to a horizontal position, which position permits the vehicle to

pass through the gate, the gate retaining such position until the vehicle has cleared the gate, whereupon the weights 25, move downwardly within the tubular posts 5 and 6, bringing the gate, to its normal, closed position.

Having thus described the invention what is claimed is:

1. A vertically swinging gate including a top and bottom bar, means having connection with the bottom bar forming hinges, a buffer bar supported in spaced relation with the lower bar, hollow posts associated with the gate, means operating within the hollow posts and having connection with the gate, for holding the gates, normally, in a vertical position, and means carried by the gate for restricting the swinging movement thereof.

2. A vertically swinging gate including top and bottom bars, means for pivotally connecting the gate to a support, a buffer bar extending transversely of the gate and in close proximity with the bottom bar thereof, hollow posts for supporting the gate, means for moving the gate in one direction, a central bar forming a part of the gate, one end of said central bar extending beyond the upper bar, said bar adapted to contact with a vehicle passing over the gate, for restricting movement of the gate.

In testimony that I claim the foregoing as my own, I have hereto affixed my signature in the presence of two witnesses.

CARL D. KELLEY.
